Filed Nov. 5, 1971, Ser. No. 196,263

Term of patent 14 years

Int. Cl. D12—16

U.S. Cl. D14—27 C

FIG. 1.

FIG. 2.

FIG. 3.

FIG. 1 is a perspective view showing the top, rear portion and open right side of the car top carrier of my design;

FIG. 2 is a perspective view thereof showing the bottom, rear portion and open left side;

FIG. 3 is a perspective view of the top, front portion and closed left side of a modified form thereof.

The right and left sides of the carrier, when closed, are mirror images of each other.

The rear of the form shown in FIG. 3 is the same as that shown in FIGS. 1 and 2. The front of the form shown in FIGS. 1 and 2 is flat and plain except for the upper carrier portion which is curved as shown in FIG. 3.

I claim:

The ornamental design for a car top carrier, as shown and described.
